UNITED STATES PATENT OFFICE

RICHARD B. BUDIN, OF BROOKLYN, NEW YORK, ASSIGNOR OF ONE-HALF TO ROBERT HATZEL, OF BROOKLYN, NEW YORK

INDOOR CLOTHES DRIER

Application filed October 23, 1929. Serial No. 401,655.

This invention relates to indoor clothes dryers, and has among its objects the provision of an improved device of the nature set forth which is adapted to automatically 5 expand in open position and to similarly assume a compact condition on being closed.

Another object of the invention is to furnish a device of the character described having improved means to permit the same to be 10 loaded in a convenient and easily accessible manner, and to permit the device to be elevated to be out of the way.

Another object of the invention is to construct a device of the type mentioned having 15 an improved mounting for causing a positive spreading of the clothes supporting means, and which mounting is movable with the loaded supporting means to any desired point.

20 Another object is to provide a device of the class alluded to which can be mounted in any desired cabinet or recess.

A further object is to provide a device of the kind mentioned having comparatively 25 few and simple parts, which is rugged in construction, inexpensive to manufacture, and reliable and efficient to a high degree in use.

Other objects and advantages of the invention 30 will become apparent as the specification proceeds.

With the aforesaid objects in view, the invention consists in the novel combinations and arrangements of parts hereinafter described in their preferred embodiments, 35 pointed out in the subjoined claims, and illustrated on the annexed drawings, wherein like parts are designated by the same reference characters throughout the several views.

In the drawings:

40 Figure 1 is a view in front elevation of a cabinet adapted to receive my invention.

Fig. 2 is a side elevation.

Fig. 3 is a view in front elevation of the device in the closed position in the cabinet, 45 as seen with the door of the latter open.

Fig. 4 is a top plan view of the device in open position, as seen at a plane 4-4 of Fig. 3.

Fig. 5 is a view in front elevation of the invention in open, raised position, certain parts 50 being removed.

Fig. 6 is an enlarged fragmentary view of the device in front elevation, showing particularly details of the mounting.

Fig. 7 is a vertical sectional view taken 55 on line 7-7 of Fig. 6.

Fig. 8 is a bottom plan view of the device shown in Fig. 7.

Fig. 9 is a view in vertical elevation of a closet for the device built into a wall.

Fig. 10 is a sectional view taken on the line 10-10 of Fig. 9.

Fig. 11 is a fragmentary view in vertical elevation of a modified mounting.

Fig. 12 is a view in side elevation thereof.

Fig. 13 is a top plan view of a modified bracket mounting.

Fig. 14 is a vertical sectional view taken on line 14-14 of Fig. 13.

Fig. 15 is a top plan view of another modification of a bracket mounting.

Fig. 16 is a view in vertical elevation taken on line 16-16 of Fig. 15.

Fig. 17 is a top plan view of a further modification of the bracket mounting.

Fig. 18 is a view in vertical section taken on line 18-18 of Fig. 17.

Fig. 19 is a top plan view of a still further modification of a bracket mounting.

Fig. 20 is a vertical sectional view taken 80 on line 20-20 of Fig. 19.

Fig. 21 is a diagrammatic view showing the mounting of a device in a room and in different positions.

The advantages of the invention as here 85 outlined are best realized when all of its features and instrumentalities are combined in one and the same structure, but, useful devices may be produced embodying less than the whole.

It will be obvious to those skilled in the art to which this invention appertains, that the same may be incorporated in several different constructions. The accompanying 5 drawings, therefore, are submitted merely as showing the preferred exemplification of the invention.

Generally described, the invention provides an indoor clothes drier which includes 10 a bracket or other supporting means, on which a plurality of bars are pivotally mounted. The pivots lie at an angle to each other, so that the bars will, in upright position, lie substantially in parallelism, or at least along- 15 side of each other, but when displaced from upright position, the said bars will diverge from each other into any required spaced relation. In this diverging or spread relation, the bars may lie in a horizontal or any other 20 suitable plane. The movement of the bars may occur as a unit or separately as shown. The pivotal coaction is such that the bars are positively guided into spread or collapsed position coincident with their movement 25 from upright to horizontal position, and vice versa. The said bars may be thought of as supporting elements, which may serve directly, or through the intermediacy of a plurality of spanning or cross members to carry the 30 clothes. It may be noted at this point that while the exemplification of the invention herein illustrated shows a clothes drier, that the scope thereof is not to be thus limited, but it may be used for drying other articles 35 also, or for supporting different articles for purposes of display, storage, chemical or mechanical treatment, and that the device including its carrying portions may be modified, where desired, to particularly adapt 40 them for the various uses. Now the transverse supporting members are so constructed as to render the entire device fully collapsible into a compact form, and these members have movable, and in a sense pivotal or 45 swingable relation with the said supporting elements. Therefore the transverse members may even be rigid, as will be readily apparent, but are preferably flexible, since that makes for simplicity in construction, and low cost, 50 where the transverse members are formed of rope. The spreading or collapsing of the supporting elements may automatically open or collapse the transverse members, and where these are made of rope, can place the same 55 under tension. To permit the device to be easily loaded in a readily accessible position and then to be moved into any out of the way location, as, for instance, by being suitably elevated, the said bracket may be mounted 60 on a guide rail or bar for movement therealong by any feasible actuating means, one form of which may consist of a rope and pulley connection.

Referring in detail to the drawings, 22 de- 65 notes a device embodying the invention. The

same includes a cabinet 23 in which the supporting means may be mounted when in closed position, so as to be inconspicuous and neat in appearance. The device can thus be used in any well ordered home without detracting from the appearance thereof. The cabinet may be of any conventional form, and as illustrated, is in the nature of an elongated box having side walls 24, a rear wall 25 to lie against a wall 26 of the building, and includes also top and bottom walls 27, and a hinged door 28. The cabinet may be mounted by means of upper and lower lugs 29 through which suitable fastenings 70 may be passed.

The position of the cabinet is preferably in a room 30 as shown in Fig. 21; that is, the cabinet is mounted at an elevation that brings only the lower portion thereof within easy access of a person standing on the floor. Thus the device may be easily used, and the supporting means within the cabinet raised to a suitable high point, as hereinafter described, to be out of the way.

Extending longitudinally of the cabinet is a vertical guide bar 31 which is positioned in substantially central relation therein. This may be of hollow or solid cross section, and of any suitable shape, preferably square. It may be secured to the cabinet at spaced points, as, for example, at the upper and lower ends thereof, by fastening plates 32, fixed to the top and bottom of the cabinet.

Mounted for sliding movement along the guide bar is a supporting bracket 33. This has a central portion having a square opening to receive the guide bar, and from this central portion extend a plurality of coplanar arms 34, which are angularly spaced. The arms 34 are forked at 35, and pivot pins or screws 36 extended therethrough. Partially projecting over each of the forks is a stop portion 37 which may be integral with the bracket 33.

To permit the bracket 33 to move easily along the guide bar 31, rollers 38, 39 are provided mounted on lugs 40. The roller 38 is at the upper side of the bracket and coacts with the rear of the guide bar, while the roller 39 is at the lower side thereof and coacts with the front side of the bar. Thus the weight carried by the bracket, which acts as a turning moment thereon, is taken up by the rollers to avoid friction or binding with the guide bar.

To move the bracket 33 along the guide bar 31, the latter is provided with a pulley 41 mounted in an opening 42 of the guide bar. Extending over this pulley is a tension element, such as a rope 43 which engages the bracket. The bracket may have lugs 44, 45, with the former of which the rope is connected by a knot 46 to raise the bracket. The lug 45 is also connected to the rope 43 but in an opposite relation as at 47 to permit the

bracket to be pulled downward if it should in some unforeseen manner bind on the guide bar 31. To retain the bracket 33 elevated, the rope 43 may have an eye member 48 secured thereto to engage a hook 49 fixed to the lower portion of the cabinet.

A plurality of supporting elements 50 are mounted at the bearings 35. These supporting elements may be of any suitable material, preferably a hard wood, and of any required shape. Satisfactory results are obtained by using a square form at the bearing, to minimize wear and afford ample bearing area. Thus the said elements have stop portions 51 adjacent to the pivots, said stop portions coacting with the stop projections 37 of the slide bracket 33. Accordingly the said elements may move upward as shown in Fig. 3, but their downward movement is limited to a substantially horizontal plane by the stop engagement aforementioned.

The coaction of the supporting elements 50 with the slide bracket 33 is such that when the elements are in upward position they are together, while in the horizontal position they are spread apart. This spreading and collapsing movement occurs automatically by reason of the angular relation of the bearings 35.

Carried by the supporting elements 50 are a plurality of relatively movable members 52 which may be permanently connected to one or both of the said elements and are, in any case, swingable with respect thereto. The members 52 may be manipulated manually or automatically coincident with the movement of the said elements.

A simple form of constructing the members 52 is to make them of a flexible means, such as rope. The latter may be of a continuous nature, threaded through holes 53 in the elements 50 to afford the suitably spaced, parallel members 52. The latter may be placed under tension by the elements 50. In the closed or collapsed position of the device, the members 52 depend evenly as in Fig. 3, without entangling. The elements 50 as well as the transverse members 52 fall readily within the cabinet 23, which may be closed.

The manner of using the device will now be clearly apparent. The operator opens the door 28, grasps the lower parts of the elements 50 and swings the same downward. The said elements spread while moving into horizontal position and simultaneously stretch the transverse members 52. The latter are loaded, and then the rope 43 is manipulated to move the bracket 33 and hence the elements 50 upward, after which the loop 48 is engaged with the hook 49. The clothes or other articles are now out of the way.

In Figs. 9 and 10 is shown an arrangement in which a closet 54 to receive the device is built into a wall 55 and is provided with a

door 56. This form may be embodied especially into houses in course of construction.

In Figs. 11 and 12 is shown a modified form of mounting in that the cabinet or closet is eliminated. A plurality of fixed brackets 57 are secured to a plate 58 which is attached to any wall 58a of the building. The said fixed brackets carry a guide bar 59. A slide bracket 33 such as that hereinbefore described may be mounted for movement on the guide bar, this modification functioning in the same manner. A hook 60 corresponds to hook 49 above mentioned. A flexible band 59a may be secured at one end to the plate 58 and at its other end by any suitable detachable fastening, to encircle the carrier elements 50 and hold the same in collapsed position.

In Figs. 13 and 14 is shown a modification which is in principle similar to those hereinabove set forth, including a guide bar 61, and a slide bracket 63. However, a plurality of supporting elements 63 are mounted to directly carry the articles or clothes. Therefore more than two of these elements are used, the bracket having a corresponding number of spaced lugs 64, through which and the elements 63 a wire 65 is threaded forming pivotal bearings. The elements 63 have stop engagement with a portion 66 of the bracket overhanging the bearings.

In Figs. 15, 16 is shown another modification of the invention including a guide bar 67, a slide bracket 68, and a plurality of carrier elements 69 operating in a manner similar to those shown in Figs. 13, 14, except that they are movable downward into collapsed position. The slide bracket has a plurality of bearing recesses 70 having pivot means 71, and there being an overhanging stop portion 72. The inner ends of the elements 69 are slotted at 73, and said ends re-enforced by straps 74. Now, on moving any element outward from the locked horizontal position shown, it may be swung downward into the dotted line collapsed position, and vice versa.

In Figs. 17 and 18 is shown another modification including a guide bar 75 and a slide bracket 76, carrying article supporting elements 77. The latter have each a central flat metal bar 78 which is slotted at 79 to receive pivot pin 80, and functions like the preceding modification.

In Figs. 19 and 20 is shown still a further modification including a guide bar 81 and a slide bracket 82 which is split along a horizontal plane into two parts 83, 84 that are secured together by screws 82a. These parts coact to form bearings 85 which have elongated internal recesses 86 to receive pivot means 87 of the individual elements 88. The latter are movable from full to dotted line positions as hereinbefore described.

It will be understood that in all of the modifications shown, the general manner of

operation is as disclosed in the principal form of the invention, and that these modifications may be mounted as in Fig. 11 or in a cabinet or closet.

5 The several parts are in all cases made to be rust proof by using a suitable metal or by plating.

It will thus be seen that I have provided a device which fulfills the several objects of the 10 invention and which is well adapted to meet the conditions of practical use.

I claim:

1. In a clothes drier, a vertical tubular 15 guide member, a bracket movable along the guide member, hanger arms mounted on the bracket, and means to move the bracket along the guide member, said means including a tension element, said guide member having an opening therein, a pulley positioned in 20 said opening and rotatably mounted on the guide member, said tension element passing over said pulley and through said opening, said tension element having both ends connected to the bracket and extending down- 25 ward along opposite corresponding sides of the bracket, said tension element having a lower portion having slack therein, and fastening means at the lower end of the guide member for detachably engaging the tension element to retain the bracket in elevated 30 position.

2. In a clothes hanger, an upright guide member having opposite flat faces, a substantially horizontal flat bracket movable there- 35 along, hanger bars having fixed horizontal pivotal mounting on one side of the bracket and having stop engagement with an edge thereof, upward and downward extending lugs on the bracket and rollers mounted on the 40 bracket lugs to avoid binding of the latter on the member caused by the weight of clothes on the arms, said rollers being vertically spaced a distance greater than the thickness of the bracket and being disposed to act on 45 opposite flat sides of the member with the lower roller on the side in which the hanger bars extend.

3. A clothes drier including a vertical 50 guide bar, a bracket movable up and down along the guide bar, and hanger bars on one side of the bracket, said bracket having a hub plate having an opening for slidably sub- 55 stantially snugly receiving the guide bars, said hub plate having upwardly and down- 60 wardly extending lugs on opposite sides of the guide bar, and rollers mounted on the lugs for laterally engaging the guide bar to reduce the friction between the bracket and the guide bar caused by the weight of the 65 hanger bars.

4. A clothes drier including a vertical 70 guide, a bracket movable up and down along the guide bar, and hanger bars on the bracket, said bracket being of elongated form 75 transverse to the guide bar, said bracket hav-

ing a pair of lugs on each end thereof, and the hanger bars being each pivoted to the bracket between a pair of said lugs, said pairs of lugs extending at an angle to each to hold the hanger bars at a corresponding angle, said bracket having an opening intermediate the ends thereof for slidably receiving the guide bar.

80 In testimony whereof I affix my signature.

RICHARD B. BUDIN.
